RESILIENT BIASED CLOSURE FOR
CONTAINER OPENINGS
Stephen V. Dillon, 2256 S. Troost, Tulsa, Okla.
Filed Sept. 30, 1963, Ser. No. 312,388
5 Claims. (Cl. 220—24)

This invention relates to a resilient biased closure for container openings. More particularly this invention relates to a reusable closure including a sealing element for sealably closing and opening a container, the sealing element also furnishing the biasing force for retaining the closure in the opening.

An object of this invention is to provide a resilient biased closure for container openings that maintains an efficient seal within the container opening.

Another object of this invention is to provide a resilient biased closure for container openings that is reusable over extended periods of time.

Still another object of this invention is to provide a resilient biased closure for container openings that is usable to sealably close openings of various sizes and shapes in containers of various sizes and shapes.

Yet another object of this invention is to provide a resilient biased closure for container openings including a gasket of resilient material that sealably closes the opening and furnishes the biasing force for retaining the closure in position in the opening.

Another object of this invention is to provide a reusable resilient biased closure for container openings that can be used in conjunction with valves, pour spouts, and similar elements to effectively sealably close the opening in the container into which these elements fit.

Further objects and advantages of this invention will be apparent from the following description and claims, with reference to the accompanying drawings forming a part of this specification wherein like reference characters designate corresponding parts are used.

General description

Generally, this invention consists of a closure device 10 for a container opening comprising a cylindrical body portion having an annular flange portion on one end thereof, and an annular shoulder portion on the other end thereof. The shoulder portion is designed to be received interiorly of the container, through the container opening. A gasket member of resilient material is adapted to be received about the body portion, between the flange portion and the shoulder portion. This gasket member is sufficiently large in area to cover the container opening no matter what size or shape whereby a seal is accomplished between the container opening and the flange portion of the closure device. Furthermore, the gasket member is adapted to apply a biasing force against a body portion to urge or askew the body portion toward an edge of the container opening. In so doing, the shoulder portion, of the body portion, contacts the interior edge of the container opening and is therein retained, until removed.

Specific description

30 For a more specific description of this invention, references now made to the figures and in particular to FIGURES 1, 2, 3 and 4. The closure member 10 of this invention comprises a retainer member 12 and a gasket member 14.

35 Retainer member 12 (see FIGURE 4) includes a slightly elongated body 16, preferably of a cylindrical configuration. Body portion 16 is provided on one end with a concentric annular flange portion 18 of substantially increased diameter and on the other end with an enlarged portion 20. Portion 20 is enlarged to provide an annular shoulder 22 at the point of juncture of portion 20 with the body portion 16. Although portion 20 can be of any convenient configuration, when body portion 16 is cylindrical it is preferred that head portion 20 be substantially hemispherical, or of a streamlined configuration.

40 Gasket member 14 is preferably a wedge of resilient rubberlike or plastic material, being substantially square or rectangular in plan view as seen in FIGURE 1, and being wedge shaped or triangular in cross section as seen in FIGURE 2. It is preferred, though not considered imperative, to the operation of this invention, that the two gasket surfaces, 24 and 26 converge to form an apex of at least three degrees. Furthermore, it is preferred, although again not considered imperative to the operation of this invention, that the angle of juncture between the surfaces 24 and 26 of the gasket member 14 be at least 90 degrees. A passage 30 is provided through gasket member 14 at right angles to the upper surface 24 to receive therein the body portion 16 of retainer member 12, in the manner shown in FIGURE 2. The diameter of passage 30 is approximately equal to the outside diameter of body portion 16.

45 With the closure member 10 assembled in this manner, the body portion 16 extends at right angles to surface 24.

and flange portion 18 lies in contact with, and parallel to surface 24. Shoulder 22 of portion 20 is oriented so as to be at an angle to surface 26 of the gasket member 14, this angle being approximately equal to the apex angle of the gasket member 14. Furthermore, it is preferred that shoulder 22 be located approximately adjacent to, or in contact with surface 26 of the gasket member 14. It should be noted that head portion 20, although enlarged with respect to body portion 16, is not too large to prevent its being forced through the passage 30 in gasket member 14.

The embodiment of FIGURES 1 through 3 includes a clip element 32 comprising an elongated, relatively thin ribbon of metallic material. One end of the clip element 32 is attached to the upper surface 34 of flange portion 18 and extends radially therefrom, substantially parallel to the surface 34. The purposes of clip element 32 will be more fully described hereafter:

In positioning closure member 10 within a circular opening 36 in container 40, the closure member 10 is placed over opening with portion 20 registering with the opening. A downwardly directed force is then applied to the upper surface 34 of flange portion 18 to cause depression of the gasket member 14, primarily in the region 37 of maximum thickness. As a result of the substantial flattening of gasket member 14, the body portion 16 becomes oriented substantially at right angles to the container wall 40 permitting portion 20 to enter the container opening. When this force is removed, the gasket member 14, because of its resiliency, tends to resume its original wedge shape with expansion greatest in the region 37 of maximum thickness. That portion of the flange 18 nearest region 37 will move upwardly more than the portion furthest from this region, thereby swinging or askewing body portion 16 into an inclined position, with relation to the container wall 40. When the body portion 16 of retainer member 12 is in this position, as shown in FIGURE 3, portion 20 will be located adjacent the peripheral edge of the opening 36 in the container wall 40. Shoulder 22 will be in contact with the interior surface of the peripheral edge portion of opening 36 at the point adjacent body portion 16 thereby preventing withdrawal of the closure member 10. In this position the gasket portion 14 is in sealing contact with the outer surface 41 of container wall 40, in an area surrounding the opening 36. The surface 24 of gasket member 14 is in sealing contact with the bottom surface of flange portion 18 of the retainer member 12. Therefore, an efficient seal is provided for the container opening 36 to prevent loss of fluid or other materials stored therein.

In order to remove the closure member 10 from sealing connection with opening 36, the body portion 16 must be rotated or pivoted into a position substantially at right angles to the plane of the container wall 40 with the shoulder portion 22 substantially concentric with opening 36 to allow withdrawal of the portion 20 from within the opening.

The clip element 32 as above described, is used to assist in this removal operation. As shown in FIGURE 3, the clip element may be a part of the original container as by a shearable connection 42 therewith. Clip element 32 is grasped at its outer free end 33 and an upward pull applied thereto will shear the solder or spot weld connection 42. This upward pull tends to pivot the flange portion 18 into a position substantially parallel to the wall portion 40. In this position, retainer body portion 16 extends at right angles to container wall 40 and the shoulder 22 registers concentrically with opening 36 thereby allowing removal of the head portion 20 of retainer member 12.

Although this closure member 10 is relatively easily removable as above described, it cannot under ordinary conditions be accidentally removed. The resiliency of the gasket member 14 causes an upward force to be applied to the bottom surface of the flange portion 18 which force

10 maintains the shoulder 22 hooked with the container edge adjacent the internal periphery of opening 36.

5 FIGURE 5 represents a simplified container closure constructed in accordance with the principles of this invention but without a spring clip. Like numerals refer to like parts heretofore described.

15 Referring now to FIGURES 6 and 7, there is shown an alternate embodiment of this invention for use with triangular formed container openings 75. Closure member 70 is of a construction similar to closure member 46 of FIGURES 1 through 5 except that gasket member 72 is of substantially uniform thickness throughout. Therefore, the biasing force required to position the closure member 70 such that shoulder 74 will be in locking contact with the interior surface of container wall 76 must result from the compression of the gasket member 72 in the space between the container top and flange 78.

In use, member 70 is positioned above opening 75 such that head portion 77 registers with a region of opening 75 that is large enough to allow passage downwardly therethrough. A downward force is applied to the top of closure member 70 to depress gasket member 72 sufficiently such that head portion 77 enters opening 75 to a point where shoulder 74 is located internally of container wall 76. A lateral force is then applied to member 70 to slide it in the direction of apex 79 of opening 75 thereby bringing shoulder 74 into locking contact with the interior of container wall 76 adjacent the apex 79 of opening 75. The externally applied downward and lateral forces are then removed and the restoring resilient force of the depressed gasket member 72 maintains the shoulder 74 in locking contact with the interior of container wall 76, adjacent opening 75.

35 Referring now to FIGURE 8, there is shown closure member 70-A, similar in construction to closure member 70 of FIGURES 6 and 7, sealably positioned within and about a container opening of configuration different from that previously shown. The opening of FIGURE 8 consists of a communicating circular opening 80 having a radial slot extension portion 82. The circular opening 80 is of sufficient diameter to accommodate the passage therethrough of the head portion 77-A of closure member 70-A. When head portion 77-A has been pressed into the circular opening 80 in a manner above described, a lateral force is applied to the closure member 70-A to force the member laterally along the radial slot extension 82 thereby locking head portion 77-A interiorly of the container to prevent accidental removal. The operation of closure 70-A within the opening 80-82 of 40 FIGURE 8 is substantially similar to the operation of closure 70 in the opening of FIGURES 6 and 7, therefore, further description will be omitted.

45 It should be noted that either of the closure members 10 and 46 could also be used to sealably close opening 80-82 of FIGURE 8 since their operation, as above described, is similar to the operation of the closure member 70-A.

50 Referring now to FIGURE 9, there is shown still another container and container opening in which the closure of this invention can be used. Container 86 is substantially box shaped and provided with a triangular opening 88 in one corner thereof sealably covered with a clear plastic film which can be punctured to open. Opening 88 is of the same general configuration as opening 75 of FIGURES 6 and 7 and can be sealably closed by any of the closure members of this invention above described.

55 Referring now to FIGURE 10, there is shown still another modification of the closure of this invention. Closure member 90 consists of a central preferably cylindrical body portion 92 having on one end thereof a flange portion 94 and the other end thereof provided with one or more external threads 96 with a gasket member 98 of resilient material received about the body portion 92. It is preferred that a washer 100 having an area at least 60 approximating the area of gasket 98, be positioned upon

92 between flange 94 and gasket 98 against which the major part of the restoring resilient force of depressed gasket 98 can be applied.

The threads 96 present an upwardly directed continuous helical shaped shoulder on the exterior of body portion 92 that functions in the same manner as the shoulders of the closure members previously described. One of the advantages gained from using external threads as the locking shoulder of the closure member is that they allow the closure member 90 to be sealably locked in opening 102 at various depths to provide seals of various strengths between the closure member and the container. A tension element 104, such as a spring, is attached at one end to the upper surface of flange portion 94, and at the other end to the container wall 105.

Spring tension element 104 produces a lateral force on the closure member 90 that cooperates with the resilient restoring force of gasket member 98 to maintain the threads 96 of member 98 in locking contact with a point on the peripheral edge of opening 102.

A locking element 106 consisting of a dog-leg shaped metallic ribbon inclines upwardly from attachment to container wall 105 into locking contact with the peripheral edge of flange portion 94, opposite the spring element 104. When locking element 106 is in locking contact with flange portion 94, body portion 92 can not be pivoted into a position perpendicular to container wall 105 and removed from the opening 102 therein.

When it is desired to remove closure member 90 from opening 102 locking element 106 is pivoted upwardly out of contact with the flange portion 94 as shown in phantom lines in FIGURE 10. The body portion 92 is then pivoted into a position perpendicular to container wall 105 with threads 96 concentric to opening 102 and the closure member 90 is removed from opening 102.

Referring now to FIGURE 11, there is shown a closure member 110 of the same general type as described in reference to FIGURES 5 and 6, which has been modified for use with a valve 112. Valve 112 is of conventional design having a depending externally threaded portion 114 which also functions as the central body portion of closure 110 with the threads forming an upwardly presented helical shoulder. A flange 116 is telescopically received about threaded portion 114, in contact with make up flange 120 on the body of valve 112. A wedge shaped gasket member 118, made of a resilient material, is received about extension 114 in contact with flange 116.

A central passage 122 is provided in gasket 118 for receiving therethrough the externally threaded tubular extension 114. Passage 122 can either be provided with internal threads corresponding to the threads on tubular extension 114 or can be of substantially small diameter than the external diameter of extension 114 so that extension 114 will have to be forced therein, thereby resulting in a tight seal between the gasket and the threads of extension 114. Valve 112 and closure 110 is positioned within an opening 124 in a container wall 126 in the same general manner as the closures above described with the threads on the exposed end of tubular extension 114 functioning as equivalents to the shoulders of prior devices.

This combination of closure member 110 and valve 112 allows for the easy installation and removal of valves in container openings. Furthermore, when using this type of installation for valves and the like, when a valve is removed, a closure member of the type previously described can be placed within the container opening 124 to sealably close that opening and to prevent escape of fluids or similar material contained within the container 126.

Referring now to FIGURES 12 and 13, there is shown the closure member 128 of this invention combined with a conventional reversible spout 129. Reversible spout 129 consists of a tubular conduit having a curved spout portion 130 and a substantially straight portion 132. An externally upset annular flange 134 is provided near the

middle of the straight portion 132 of the spout. External threads 136 and 140 are provided on the straight portion 132 of spout 129, on either side of the flange 134.

In attaching the spout 129 within a container opening 142, a washer 144 is slid over the end of the straight portion 132 into contact with 134. An expansible, substantially wedge shaped gasket 146 of the type previously described is positioned around the end of straight portion 132, adjacent washer 144. Therefore, straight portion 132 of the spout 129 functions as the cylindrical body portion of the retainer member 128 of this closure device and the threads 140 on the end of the straight portion 132 function as the shoulder of the retainer device similar to threads 96 in FIGURE 10. Threaded end 140 of the combination of closure member 128 and spout 129 is inserted into the container opening 142 and retained therein by locking contact of threads 140 with a point on the peripheral edge of opening 142.

When it is desired to close the opening 142, the combination closure member 128 and spout 129 is removed from container 142, the flange 144 and gasket member 146 are removed from the straight portion 132 of spout 129 and are placed upon the spout in the manner shown in FIGURE 13. The spout 129 is then replaced within the opening 142 with the curved portion 130 extending interiorly of the container and the combination locked therein in the manner above described. A cap 150 is then threadably attached to the threaded end 140 of the straight portion 132 to completely seal the opening 142.

It is necessary that the passage 144 in gasket member 146 through which spout 129 extends be smaller in diameter than the external diameter of spout 129 so that a seal is provided between gasket member 146 and the exterior of spout 129 to prevent escape of fluids or other materials from the container.

It should be apparent from the foregoing description that the closure device of this invention provides a device that operates efficiently and easily to seal and reseal an opening in a container. The device can be used to effectively close an opening of almost any configuration in a container. Furthermore, this device can be used in combination with other elements such as valves, flow spouts, inlet tubular extensions and the like, for flowably and sealably attaching such elements into a container.

The fact that the only element of this closure device that is effected to any appreciable degree by continued use is the resilient gasket which is relatively inexpensive and easily replaceable, adds economy to the many other advantages of the device.

Further, the devices of FIGURES 1 through 10 are of such height that other like containers can be stored on top without interference to cause toppling.

The invention has been described by reference to specific and preferred embodiments. It will be apparent, however, that many modifications can be made without departing from the spirit and scope of the invention. Accordingly, this invention should be construed not to be limited to the embodiment herein described but should be limited only by the scope of the appended claims.

What is claimed:

1. A closure device for a container opening comprising the combination of:
  - a retainer member having an elongated central body portion terminating one end with an integral flange portion and the other end with an annular shoulder portion; and
  - a gasket member surrounding said body portion between said flange portion and said shoulder portion and having upper and lower planar intersecting surfaces to form a taper, whereby a seal is accomplished between said container opening and said flange portion.
2. A closure device for a container opening as in claim 1 wherein said body portion is hollow to form a fluid passage spout.

3. A closure device for a container opening comprising the combination of:

a retainer member having an elongated central body portion terminating one end with an integral flange portion and the other end with an annular shoulder portion; and
 a gasket member about said body portion between said flange portion and said shoulder portion and having the surface of said gasket adjacent said flange portion downwardly tapered toward the surface of said gasket adjacent said shoulder portion, from one extremity of said gasket to the opposite extremity, and

5

10

said body portion extending through said gasket perpendicular to said tapered surface of said gasket.
